UNITED STATES PATENT OFFICE.

JOSEPH BECKER, OF WASHINGTON, DISTRICT OF COLUMBIA.

FINDER.

1,210,137.

Specification of Letters Patent. Patented Dec. 26, 1916.

Original application filed February 17, 1905, Serial No. 246,169. Divided and application filed October 10, 1916, Serial No. 124,832. Divided and this application filed November 23, 1916. Serial No. 133,093.

To all whom it may concern:

Be it known that I, JOSEPH BECKER, a citizen of the United States, residing at Washington, in the District of Columbia, 5 have invented a new and useful Improvement in Finders, of which the following is a specification.

The present application, identified for convenience of reference as Case Ao, is a 10 "continuation" of my prior and herein merged application Case An, which was filed October 10, 1916, as "Division one" of my Case J, Serial No. 246,169, filed February 17, 1905, and it relates to certain features of said Case J which are separately patentable under the head of finders, such patentable features being placed on a more scientific and precise foundation in the present application, Case Ao, by the introduction 20 of what I call the co-center K.

My present invention consists in improvements on the eccentric lens finder disclosed in my prior application, Case Ah, Serial No. 87,987, filed March 31, 1916, as a division 25 of my Case C now Patent 1,178,476; and it is incidentally related, by way of its removable lens element of Figure 8, to the invention shown in my Case AL, Serial No. 110,310, filed July 30, 1916, as a division of 30 my case F now Patent 1,198,947.

A "simple" eccentric divergent lens, as compared with the most nearly corresponding "centric" divergent lens, necessarily comprises much thicker parts whose refracting face elements are set at a considerable 35 inclination to each other, and are, therefore, apt to produce, in the finder rays, excessive refractions, and as a result, in the finder image, effects of barrel distortion which do 40 not necessarily interfere with the operation and use of the finder, but which are nevertheless objectionable.

The barrel distortion produced in the equi-concave type of eccentric lens, for instance, is so great, that I have always preferably used plano-concave lenses instead, placing them as shown in Fig. 8 of my said Case C with the plane face turned toward the object. Distortion is further reduced, I

have discovered, in a very marked degree 50 by tilting the thicker edge of the lens toward the object so that the principal axis of the lens, instead of being horizontal as indicated in the said Fig. 8 of my said Case C, shall be inclined to pass close by, or even 55 into the observer's eye; and this last feature constitutes the gist of my present invention.

The principle involved in inclining the single eccentric lens is also applicable to compound eccentric lenses; but in these, 60 there is a special advantage in applying the principle to each element separately, and as a result the principal axes of the two component lenses can not be alined or even parallel; but the main or common axis of the 65 combination is inclined, as in the single eccentric lens.

Incidentally my invention consists in a specially convenient form of mount for the rear or eye lens of the combination to facilitate 70 its removal from the position of use, either for long focus work or for cleaning.

In the accompanying drawings:—Fig. 1 is a vertical section of a single half lens form of my improved finder of the type having a 75 reflected bead sight 108" as in my said Cases C and J, except that the lower mirror 107 is shown fixed because it need not be pivoted when it is not used as a focuser element. Fig. 2 shows how two single half lens finder 80 lenses L and L' are conveniently cut out of a single full centric lens. Fig. 3, with related equations annexed thereto as a part thereof, is a diagram illustrating and serving to prove the geometrical properties of what I 85 call the co-center K, which has the remarkable optical property of being the focus of all in-glass rays whose air elements suffer minimum deviation. Fig. 4, with a related equation annexed thereto as a part thereof, 90 is a diagram showing a full centric lens whose two face centers R' and S', and co-center K, are arranged and spaced in the same manner and at the same inclination as the three corresponding centers R', S', and 95 K of the half lens L in Fig. 1; and, therefore, this full lens of Fig. 4 comprises an eccentric segment C—4—5 which has the same

shape, size, inclination, and refractive properties as the half lens L used in Fig. 1. Fig. 5 is a diagram of an equi-concave lens whose co-center K is at infinity, so that all minimum rays such as U—U'' and V—V'' have their in-glass elements U'U'', and V'V'' parallel to the lens axis, and are finally transmitted as apparently diverging from the virtual focus K''. Fig. 6 is a diagram 10 of the same lens as in Fig. 5, but "bent" to bring its co-center K from right infinity in toward the lens, the bending process being continued until the first or left face of the lens has become flat, and showing how the 15 two minimum rays U—U'' and V—V'' of Fig. 5 have, during the bending process, been slued around to meet at the right in the real focal point K'', which is the image of the co-center K in its new position. Fig. 7 is a correct drawing showing how the eccentric lens 20 having minimum deviation, is designed to yield a given angular field ZAZ' of 90 degrees for a given position E, of the observer's eye; all angles and dimensions being correctly drawn but made specially large and 25 clear by using a very thick lens and selecting an optical glass of the highest available refractive index, nearly equal to 2. Fig. 8 is a vertical section of a compound form of 30 finder, with the rear lens hinged for quick removal, such arrangement being useful, not only to facilitate cleaning of the inside lens faces, but principally to permit of quickly and conveniently increasing the focal length 35 of the finder when the cooperating camera objective is also compound and comprises an element that is removable for long focus work.

Improvements to secure a more perfect image.—These improvements relate mainly 40 to the eccentric lens and consist principally in so building and setting it in its mount or on the camera that its principal axis, instead of being parallel with the principal axis of 45 the camera objective, as in my said prior Case C, and Case Ah division of C, shall lie in an inclined position thereto, so as to pass close by or even into the operator's eye. When the finder lens is composed of but a 50 single lens, this condition is satisfied by properly inclining the lens, to tilt its thicker edge forward, that is, in a direction away from the camera plate or film or away from the operator and toward the object. Referring to the diagram, Fig. 8 of my said prior Case C, this tilting may be supposed 55 to take place about the thinnest point of the lens so that it shall have no tendency to displace the central point of image f. The 60 only effect and object of such tilting is then to reduce distortions in the image f as explained fully hereinafter, and, therefore, the general principles predicated of such lens and image in my said prior Case C apply

without any further qualification to the tilted lens of the present application Case An, and they need not be repeated herein.

In Fig. 1 of the accompanying drawings I show my improved form of single-lens field-finder, the general arrangement of which is 70 the same as in my said prior Case C.

L is the simple finder lens, which has its outer face 100 slightly concaved to avoid excessive curving of the rear face. This lens is tilted as indicated by the inclination of its 75 principal axis R'CS'K.

The inclination shown is that in which the image formed by the lens is the most nearly perfect. That is, if the lens were tilted either farther or less than shown deformation would be introduced in the finder image, due to variations in refraction. In the best position the rays of light that pass through the thicker parts of the lens in their course through the lens meet the lens faces 85 at equal angles, and suffer the least refraction; and from theoretical demonstrations which I give later on, it will appear that a divergent lens which is at all suitable as a 90 finder lens, will, when mounted as here specified, usually send all or nearly all of its minimum rays into the observer's eye.

A slight tilting either way from the best position does not appreciably distort the image and, therefore, a certain latitude is 95 allowable in mounting the lens.

The best inclination of a given eccentric lens is very easily found by direct experiment in the following manner. Observe through it almost any object, holding the 100 lens on a level with the center of the object and with its deeper concave face toward the observer. The point of view should be enough higher than the lens to center the image of the object in the lens. Then tilt 105 the lens back and forth, noting that the vertical dimension of the image varies, and that in tilting from one extreme position to the opposite extreme position the said vertical dimension of the image will first increase 110 to a certain maximum and then decrease. It is in an intermediate position where the image is tallest that the image has the least distortion and that the lens is at the proper inclination.

As a rule lenses that are plano-concave, or nearly so, will be properly enough inclined when the general direction of the concave or eye face of the lens is vertical, that is, when the lens is mounted in the camera with the 120 general direction of its deeper concave face parallel with the camera plate.

My invention involves certain geometrical relations which are peculiar to it and which I shall now set forth.

The extreme finder rays 120 and 121 produced beyond the lens L intersect in a point A at an angle w which is equal to the cor-

responding angular value of the camera field. The refracted parts 120' and 121' of these same extreme rays proceed to meet in the operator's eye at E. Points E and A 5 are, therefore, conjugate foci of the lens and must be in alignment with C which represents the thinnest point of the lens as well as its two, in this case, nearly coincident nodal points. Moreover, as by the 10 present invention the principal axis R'CS' of the lens passes close by or even into the eye E the focal length f of the lens can be derived directly from the standard lens formula:

15

$$\frac{1}{f} = \frac{1}{CA} - \frac{1}{CE}$$

It should be noted that A is not a purely imaginary point, for any person being photographed sees, in A, a reduced image of the operator's eye E, and the extent of field seen by the eye E through lens L is exactly the same as would be seen if the lens L were removed and the eye E were shifted to A. I, 20 therefore, call A the "virtual eye" or the "virtual position" of the operator's eye.

Point R' is the center of curvature of the first refracting face of the lens L, and point S' is the center of curvature of its second refracting face; so that R'S' is the principal axis of a full lens, such as lens L²L³, Fig. 4, in which the present lens L was comprised as eccentric segment C—4—5. Point K, also on the principal axis R'S' is what I call the 30 co-center K of the lens. We shall presently see that in all divergent lenses which are suitable as finders, either centric or eccentric, this co-center K of the lens is located somewhere between the finder and the observer's 35 eye.

My co-center K is found as indicated in Fig. 3 and in Fig. 4, by drawing, and if necessary, extending the line PQ' which connects the respective ends P and Q' of 40 two parallel radii R'P and S'Q', exactly as in finding the old optical center C, except that one of the two radii, the one that proves most convenient, here S'Q', must be reversed. The reversal is made plain in Fig. 45 50 3, where the process followed for finding the old optical center C is illustrated in conjunction with that to be followed in finding my co-center K.

Fig. 3, for clearness, shows a lens of considerable thickness R to S, but drawn to scale and in which the radii RR' and SS' are both positive, so that the equations which are annexed to the figure as a part thereof, may easily be verified by computation as 55 60 well as by scale.

The optical center C, Fig. 3, may be defined as the geometrical point C of the lens axis R'S', through which is directed any in-glass ray, such as ray PQ, which connects

parallel surface elements of the lens, these 65 elements being indicated by heavy shading at P and Q.

My co-center K, Fig. 3, may similarly be defined as the geometrical point K of the lens axis R'S' through which is directed any 70 in-glass ray, such as ray PP', which connects surface elements P and P' of the lens that are anti-parallel with reference to such in-glass ray PP'.

The ray PP' is the minimum ray of the 75 prismatic lens element which it traverses, for it meets the two refracting faces of the lens at angles that are equal but oppositely directed. The equality of these oppositely directed angles at P and P' is proved, in 80 Fig. 3, by observing that TP and S'Q' being parallel by construction, must determine with the two straight lines crossed in P', two similar triangles TPP' and S'P'Q'. The latter triangle S'P'Q', whose sides S'Q' and S'P' 85 are invariable radii, is necessarily isosceles, and therefore TP and TP', which are the normals to the surface elements at P and P', are equal in length and equally inclined on the ray PP'. This proposition is true for 90 any possible inclination of the ray PP'K. Thus, in Fig. 4, noting that the in-glass rays 2—3, 4—5, 6—7, 8—9, all converge in the co-center K, we can be sure that each is the in-glass element of a ray whose two air 95 elements suffer minimum relative deviation; and, we can be equally sure, that an in-glass ray, such as 8—10 which is directed to miss the co-center K, is the in-glass part of a ray 100 whose two air elements suffer a relative deviation that is greater than the minimum.

My co-center K and the optical center C are alike in that their distances to the centers of curvature R' and S' are proportional to the radii of curvature r and s ; but they differ in that one of the radii used for determining the co-center K must be an imaginary or reversed radius, such as the radius S'Q' used in Fig. 3, and in Fig. 4.

In Fig. 3 it will be noted that the distances CS', CR' are both positive, whereas the distances KS' and KR' differ in sign, for KS' is negative and KR' is positive. The difference between the two centers C and K may accordingly be expressed algebraically as follows:

$$\frac{CR'}{CS'} = +\frac{r}{s} \quad (1)$$

$$\frac{KR'}{KS'} = -\frac{r}{s} \quad (2)$$

120

That is to say my co-center K is really the optical center of a lens whose second face would be at S'' instead of at S, and whose 125 thickness would be RS''.

The positions of centers C and K are more conveniently determined by means of

the following equations whose proof, for the optical center C, is fully given in Coddington, "A Treatise on the Reflexion and Refraction of Light, Being Part I of a System of Optics," Cambridge 1829, pages 88 and 89 (copy at the Library of Congress).

$$RC = \frac{rt}{r-s} \quad (3)$$

$$RK = \frac{2rs+rt}{r+s} \quad (4)$$

My symbols r , s and t , are the same as those used by Coddington except that his convention with reference to signs is different; but the final result is the same.

The divergent lenses used as finder lenses are comparatively thin, and may be considered as lenses having their two nodal points, as well as the three points R, S and C, of Fig. 3, all merged in the single point C of Fig. 4, for, if in equation 3, we make t equal to zero, RC also becomes zero. But if we make t equal zero, in equation 4, we obtain

$$RK_{(t=0)} = \frac{2rs}{r+s} \quad (5)$$

or, in a thin lens, Fig. 4,

$$CK_{(t=0)} = \frac{2rs}{r+s} \quad (6)$$

From this we easily derive

$$\frac{1}{CK} = \frac{1}{2} \left(\frac{1}{r} + \frac{1}{s} \right) \quad (7)$$

which is a very important equation, for the three reciprocals

$$\frac{1}{CK}, \frac{1}{r}, \frac{1}{s}$$

represent "curvatures" and, the equation states that an arc M'CM'', struck from K as center, has a curvature

$$\frac{1}{CK'}$$

which is equal to the average curvature of the two lens faces.

If the lens of Fig. 4 could be made of a material having a very high refractive index, say as high as ten, it would, for the same focal length, be of very nearly uniform thickness and its general shape would be a very close approximation to this circular arc M'CM'', whose center is in K.

The curve M'CM'', Fig. 4, therefore, is a very exact physical representation of what is frequently referred to in optics as the "shape" of the lens; and as it divides the lens into two lenses L², L³, which are equal in power, it may be called the "bisecting interface" of the lens.

The bisecting interface M'M'' of an equi-concave lens, Fig. 5, is plane, whereas that

of a plano-concave lens Fig. 6, is curved; and the "curved lens" of Fig. 6 may be considered as having been formed by "bending" the "plane lens" of Fig. 5.

The principal effect produced in "bending" a lens is to shift its co-center K, for the optical center C, (Figs. 5 and 6) remains almost stationary, and the changes produced in the focal length are generally negligible.

The best extant finders of the centric divergent lens type are "curved lenses" and they must be used with their "convexity" turned toward the object. The reason for this appears clearly on noting what takes place in the plano-lens of Fig. 6, which we must henceforth consider as a "curved lens" with its convexity toward the object. Here, the eye E, by simply moving up into coincidence with K'' will receive each and every one of the minimum rays that passes through the lens; and when the eye is not exactly at E, it receives rays that have not suffered much more than minimum deviation.

With the equi-concave or "plane lens", Fig. 5, which we might for convenience refer to as the "flat lens", the eye cannot possibly receive more than one of the minimum rays at a time, for the finally emitted parts of all minimum rays diverge from a virtual focus K'' situated beyond the lens.

The plano-concave or "curved lens" of Fig. 6, if turned to face the other way, would be worse than the flat lens, but it should be noted that it is really used in what is known as its "reversed" position, because its spherical aberration, for points in the image, is several times larger in such "reversed" or plano-concave position of Fig. 6, than it would be if turned around.

From equations given in lines 8 and 13, page 149, Article 125, of Heath, *A Treatise on Geometrical Optics*, Cambridge, 1895, we easily derive for the relative value of the two focal aberrations:

$$\frac{\text{Aberr. plano-concave}}{\text{Aberr. concavo-plane}} = \frac{\mu^2}{\mu^2 - 2\mu^2 + 2} \quad (8)$$

If therefore we assume that the refractive index of the "plano-concave" lens in Fig. 6 is mu equal one and a half ($\mu=1.5$), then according to this equation 5 its spherical aberration for the central point of the image is twenty-seven sevenths ($27/7$) or nearly four times greater than it would be if the lens were reversed to act as a "concavo-plane" lens; and it would be exactly four times greater if the refractive index were as high as 2. (In confirmation, see table of aberrations on page 118 of Czapski, *Grundzüge der Theorie der Optischen Instrumente nach Abbe*, Leipzig, 1904.) Spherical aberration in the image, however, is practically of little consequence because a divergent lens finder is virtually provided with an "entrance pupil" or stop opening

which is of pin-hole size, for such stop is nothing else but the diminutive pupil of what I have called the "virtual eye" at A in Fig. 1. Distortion in the image, therefore, is the only defect that need receive any attention, and this is reduced in a very appreciable degree by the use of "minimum rays."

It is always possible to design a finder lens so that each and every ray received by the eye shall be a "minimum ray." Let it be required, for instance, to design the minimum-ray finder lens, which will show to an eye at E, Fig. 7, a field of ninety degrees, through the window 12. Through the top and bottom edges of the window 12 draw the limiting rays Z and Z' of the finder field, and produce them until they meet in A, which is the position of the "virtual eye." Draw AE as principal axis of the lens to be, and DE as the desired position of the highest ray from the finder to the eye. Plot equal distances DP, DP' to determine the desired thickness PP' of the lens, at its upper edge, as well as the direction PP' of the in-glass part of the highest minimum ray ZPP'E. Produce PP' to locate the co-center K on the principal axis AE. Now plot PX and PY of any lengths such that the ratio PX/PY shall equal the refractive index mu D(μ_d) of the glass to be used, and XY so determined is the exact direction of the normal PT at P.

The triangle PXY, I call the "refractive triangle" because its angles at Y and X are respectively equal to the angles of incidence and refraction at P; for, in this triangle, we evidently have.

$$\frac{\sin Y}{\sin X} = \frac{PX}{PY} = \mu_d \quad (9)$$

A second "refractive triangle" P'X'Y', in every way similar to the former PXY, determines the direction P'T of the normal at P'. Producing the normals TP and TP' we locate the two centers of curvature R' and S', on the principal axis AE of the lens, and the two lens faces can now be drawn by taking R'P for the radius of the first face R of the lens, and S'P' for the radius of the second face S. If no error was committed, S'Q' drawn parallel to PR' should meet the line PK and the circle SS' in the same point Q'. This lens RS, therefore, has its co-center in K. The image of K in the first lens face R coincides with the virtual eye at A, and its image in the second lens face S coincides with the real eye at E. Any ray received at E must, therefore, be a minimum ray, for any possible spherical aberration at focus A does not appreciably change the nature of the ray received.

The lens of Fig. 7 has its first face convex because its field angle ZAZ' and its refractive index have exceptionally high values;

for, when both of these factors are low, as occurs in current practice, the same graph of Fig. 7 produces a lens of the general shape seen in Fig. 1.

Concavo-convex prism.—Onto the face 100 of the lens L, Fig. 1, is cemented the prism 101 which has its cemented face made convex to fit face 100. The under face 102 of the prism is also curved, being made concave to the same radius as the face 100 of the lens. This is in order that the reflected rays shall traverse two curved surfaces similar to those traversed by the direct rays, and shall, therefore, produce a reflected image *i* on the same scale as the directly formed image *f*. The reflected rays also traverse the cemented curved surfaces, but they pass through them without being refracted as if the prism and lens were made of one piece of glass.

The lens L being inclined to secure the best image, the prism supported thereby must be ground so that its reflecting face shall likewise be properly inclined. The certain latitude allowed in the angular set of the lens allows of a corresponding latitude in the accuracy with which the prism is to be ground. The forward tilt of the lens holds the prism clear of the lower edge of the lens and, therefore, the prism need not have its upper edge ground down as indicated at 40, Fig. 10 of the said prior Case C. The side faces of the prism, to be invisible to the observer and leave a sharp cut separation between the apparent parts of the two images *f* and *i*, should be directed to point A, which is as before noted the virtual position of the observer's eye. Face 102 might also be exactly directed on A with the same object. In the figure the general direction of face 102 passes a little below A.

The operation of this concavo-convex prism 101, is made clear by considering its action on the rays which proceed upwardly from the sight wire 108. It first forms, by refraction, the image 108', then, by reflection, the image 108'' which serves as bead sight for the finder.

The mirror 107 is essentially a focuser element, but its presence is necessary here to complete that part of the finder image which, without mirror 107, would appear black in the peep mirror 101, and its main purpose is to supply, in so completing the image, a lighted background for the black sight wire 108 whose image 108', formed by the concave surface 102, as just explained, serves as original for the final image sight 108''.

Image 108'' in coöperation with the peep mirror determines the height of the observer's eye; but the position of the eye in azimuth is determined by the peep mirror and the bead 25 on the camera box.

In the present form of eccentric finder, 130

Fig. 1, the lens L does not, as in some other forms, have to be of any certain degree of eccentricity, because the direction of the finder field is determined by sights (peep 101 and image 108'') which are both located in the object space of lens L where they act exclusively on the incidental finder rays. Any change made in the eccentricity of the lens L, therefore, simply raises or lowers the height of the eye E, and such height is immaterial, in the present form of finder, as long as it is sufficient to insure that the lowest utilizable ray 121' emitted by the finder is not obstructed by the edge of the camera box, near bead 25. The lens L shown in Fig. 1 is an exact half lens because I preferably use half lenses, as they are easily made by simply splitting full lenses diametrically, as shown in Fig. 2. The half lens is, in fact, a very practical and useful form of my eccentric lens; but its main advantage resides in a feature which can only be utilized when complementary half lenses are used together as in my Case Ap, Serial No. 133,162, filed Nov. 24, 1916; and, therefore, all claims on the half lens form of eccentric lens are made in my said Case Ap.

Compound eccentric lenses.—The principles of construction given above for single finder lenses apply to compound finder lenses, but not so strictly because a two lens finder, for instance, as compared with a single lens finder of the same focal length has shallower curves and as a rule produces much less distortion in the image. Considerable latitude, therefore, is allowable in the designing and mounting of the elements of a compound finder lens or of the compound finder as a whole. However, the principles given above to reduce distortion in single lens finders can be applied with advantage to reduce aberrations in the compound lens finders; especially is this so when the front element of the compound finder is to be used singly for long focus work, as in Fig. 11 of my said Case C. The principle is first applied to the front lens used singly, as explained in connection with present Fig. 1, and then it is also taken into account in adding the other lens or lenses. The result of such process leads to a form of type shown in present Fig. 8, which also contains other novel features. The parts that are omitted in Fig. 8 are substantially the same as seen in Fig. 1, except that the bed of the camera is usually extended to support a second cam for long focus work as set forth in Fig. 11 of my said Case C.

The finder frame 500 has a cross piece 501 which forms a box-like frame in which the front lens L^s is firmly fixed by means of cement or clamps. Point C^s, represents the two, in this case, nearly coincident nodal points of the full centric lens which comprises L^s as eccentric segment, and it also

marks the thinnest point of such centric lens. The upper rear part 502 of the frame 500 is hinged to the frame proper at 540 so that it may be turned down into the dotted position. This hinged part has firmly fixed therein the rear lens L^e. Point C^e represents the two, in this case, nearly coincident nodal points of the full centric lens which comprises lens L^e as eccentric segment, and it also marks the thinnest point of such centric lens. In Fig. 3 of my said prior Case C, the rear lens is mounted so it may easily be unmounted and removed for long focus work; the rear lens L^e here shown is removed without being unmounted, simply by being turned down into a position where it is out of the way; and, when turned up, it is held closed by a spring catch 515.

The front lens L^s is inclined according to the principles of Fig. 1. Supposing the rear lens to be in its turned down or dotted position, the extreme finder rays 510, 511, limiting a field represented by angle v when produced without refraction, meet in A^s, which is the virtual position of the operator's eye for long focus work.

For short focus work the extreme finder rays limit a field 2v which may have any value required by the camera, but is here supposed to have just twice the value of v, because this is the usual proportion between the short and long focus fields of the camera. These extreme rays 510', 511', produced without refraction, meet in A^e, which is the virtual position of the observer's eye for short focus work. But the rays 510', 511', in passing through the first lens L^s, are refracted and really proceed toward a point A' situated on the secondary axis C^s A^s of the front lens L^s. The point A' is the virtual position of the operator's eye for the rear lens and is used according to the rules given above to find the eccentricity or center C^e and the focal length of lens L^e, just as A^s was used to find the eccentricity or center C^s and the focal length of the front lens L^s. The point C^e so determined generally falls very close to or even on the secondary axis C^s A^s of the front lens L^s so that the main axis C^s C^e of the compound lens produced passes in or close by the operator's eye.

The inclination of the front lens L^s being determined as just explained, the prism 503 cemented thereon should preferably have its cemented face ground so that its reflecting face shall be inclined to properly reflect the central ray a' b c d' coming along a' b from the pivoted mirror corresponding to mirror 107, Fig. 1; for, when this is not done, the lower mirror must be made larger, that is, rather larger, as seen in Fig. 1, to make sure that it will fill the prismatic mirror. It should be noted, however, that

the front lens L^s , being usually a long focus lens, can be set less inclined than shown in Fig. 11, or even more inclined, without materially affecting the finder image. As a rule, therefore, I prefer to use a common 45 degrees prism for prism 503, and to set the front lens so it will hold the reflecting face of the prism in the best position with respect to the pivoted mirror, as set forth in my said prior Case C, and to apply the corrections for distortion solely to the rear lens. In this way I am enabled to show the greatest possible extent of the second image consistent with compactness, by using the largest possible prism, and the prism used is of a standard type. Thus are secured at the same time efficiency, compactness and facility of manufacture.

The rear lens L^s can be very loosely mounted, even to the extent of having a certain play on its hinge 540, but the front lens L^s , when it carries the eye mirror as here shown, should be firmly connected with the frame and may be conveniently fixed there-to by means of plaster of Paris.

The separable form of eccentric lens finder may be used without the mirrors purely as a field finder and is also useful even in combination with cameras that have not a separable compound objective. In such cameras it still presents the advantages of forming a very perfect finder image and of having its inner lens faces easily accessible for cleaning.

The doublet of Fig. 8 has the proportions required to divide the work of refraction equally between the two lenses. In the doublet of Fig. 8, as in the single lens of Fig. 1, the eccentricity is variable within wide limits because the direction of the line of sight is fixed by sights or range points located in the path of the incident part of the central finder ray. Exact half lenses, therefore, may be used in Fig. 8, as in Fig. 1, and for the same reasons, provided the two half lenses used have the different focal lengths required to secure finder fields having the two desired different angular values.

Where the doublet is to have but one field value, and is made separable, simply to facilitate cleaning, the two half lenses used may have equal focal lengths as in my said Case Ap, where I make, as before stated, all claims on the half lens form of finder.

NOTE 1.—The principle that minimum deviation favors orthoscopy is one of the oldest in the art. It was considered common knowledge, as early as 1827, by Airy, who is the original discoverer of the orthoscopic or tangent condition. See *Transactions of the Cambridge Philosophical Society*, vol. III, 1830, page 3, lines 11 to 17.

NOTE 2.—Airy, however, explains at length (page 3, line 18, to page 4, line 16)

that the principle of minimum deviation is not, and cannot be applied generally for, in many cases its use is inconsistent with other essential requirements.

NOTE 3.—I believe that I am the first to make a clear disclosure of what these "essential requirements" must be in any camera finder of the divergent lens type. My eccentric lenses, moreover, include heavy and heretofore unused marginal parts of the lens, whose use involves unusual conditions, and these demanded original investigation, which eventually led to my discovery of the hitherto overlooked but very important co-center K.

NOTE 4.—The co-center K is a valuable contribution to lens theory as well as to lens practice, in that it helps to explain and render more scientific and precise, many well established, but not clearly understood empirical rules of lens construction.

NOTE 5.—Herman, *Geometrical Optics* Cambridge, 1900, page 196, gives a table with full data for the construction of a number of lenses, either convergent or divergent according to the sign of the focal length f , and having the certain radii of curvature rho (ρ) and sigma (σ) which insure minimum spherical aberration for parallel rays received on the more highly curved or rho (ρ) face of the lens; but correction for spherical aberration in the image is not necessary, for reasons given above in connection with Fig. 6, and the only defect to be considered is distortion.

NOTE 6.—Herschell describes a lens which may be made of such proportions that it shall be not only stigmatic but "rigorously aplanatic" for points such as A and E of my Fig. 7, for instance. (See Fig. 53, Articles 287 and 304 of Herschell's treatise on "Light" in the *Encyclopaedia Metropolitana*, London, 1845, vol. 4, pages 341 to 586. Copy at Library of Congress).

NOTE 7.—Such Herschell lens of Note 6, however, would have several objections, to wit: first, it would be extremely large, for its distance SA from A, in my present Fig. 7, would have to be a trifle larger than the distance AE; secondly, it would strictly satisfy the "sine condition" of Abbe which, for angles as large as those used in a finder field, is so inconsistent with the orthoscopic or "tangent condition" of Airy as to cause, in the present case, a very high degree of barrel distortion; thirdly, it would not utilize the "minimum rays" for its co-center K would be situated to the left of the virtual eye at A instead of to the right of it.

NOTE 8.—My first illustrated disclosure of an optical finder element, mechanically guided for convenient removal by a single motion of the hand, was made July 8, 1901, in original Fig. 2 of my said Case F, sub-

stantially as reproduced, and now seen, in Figs. 1 and 2 of my Case AL division of F.

NOTE 9.—My French patent 308,848, filed March 9, 1901, without showing, already al-
ludes to a mechanically guided removable 5
finder element, at the place where it says
that for long focus work "you put down or
you withdraw" ("on rabat ou on retire") the
rear lens of the finder. The rear finder lens
10 actually shown in the drawings of the said
French patent, however, cannot be moved
away from its position of use in any man-
ner except by unmounting it, and this, more-
over, necessitates the preliminary and tem-
15 porary unmounting of the front lens.

NOTE 10.—My said Case C, based on the
said French patent, referring to the removable
finder element (page 5, line 70) uses the
term "removed", for two different reasons:
20 first, because the term "removed" (accord-
ing to *Webster's International*, 1890) is ge-
neric as to all methods of removal really
contemplated in such Case C, and, secondly,
25 because it is more exactly descriptive of the
special method of removal that can alone be
used in the structure shown in said Case C.

NOTE 11.—The finder lenses seen in Fig. 3
of my said Case C are both slightly inclined;
but such inclinations are comparatively small
30 and are accidentally present as incidental to
other features, so that the axial line which
passes through the thinnest point of the
front lens and the thinnest point of the rear

lens, is horizontal, instead of being inclined
as it is at C^s C^e in my present Fig. 3.

NOTE 12.—Any eccentric finder lens, that
is already good with its principal axis hori-
zontal, has its image forming qualities im-
proved by inclining it as herein set forth;
hence the invention, in this particular, is not
dependent upon the exact shape of the lens.

What I claim as my invention, and desire
to secure by Letters Patent, is:

1. The combination with a photographic
camera, of a finder mounted thereon consist-
ing of an eccentric lens set with its principal
axis inclined with respect to the principal
axis of the camera.

2. The combination with a camera, of a
compound eccentric lens finder, such lens
having the line joining the optical centers of
its elements inclined with respect to the
principal axis of the camera.

3. The combination with a camera of a
compound eccentric lens finder therefor
mounted on the camera so as to admit finder
rays distinct from the camera rays that are
directed to enter the camera objective, said
finder having one of its elements hinged to
permit of turning said element out of the
path of the rays through the finder or back
into said path.

In testimony whereof, I have signed my
name to this specification.

JOSEPH BECKER.
